UNITED STATES PATENT OFFICE.

AXEL F. BERGQVIST, OF FAIRFIELD, IOWA, ASSIGNOR TO HIMSELF AND DAVID LOCKE, OF SAME PLACE.

SULKY-PLOW.

SPECIFICATION forming part of Letters Patent No. 234,743, dated November 23, 1880.

Application filed September 4, 1880. (No model.)

To all whom it may concern:

Be it known that I, AXEL FERDINAND BERGQVIST, of Fairfield, in the county of Jefferson and State of Iowa, have invented a new and Improved Sulky-Plow; and I do hereby declare that the following is a full, clear, and exact description of the same, reference being had to the accompanying drawings, forming part of this specification, in which—

10 Figure 1 is a side elevation with the near wheel removed. Fig. 2 is a vertical section through the line $\alpha\alpha$ of Fig. 3. Fig. 3 is a rear elevation. Fig. 4 is a plan view.

My invention relates to certain improvements 15 in sulky-plows; and it consists in the peculiar construction and arrangement of parts for raising and lowering the bail to which the plow is attached and simultaneously adjusting the wheel which runs upon the landside.

20 It also consists in the peculiar means for connecting the plow-beam to the bail, and also, further, in the peculiar construction of the frame or carriage, as hereinafter more fully described.

25 In the drawings, A represents the main axle, which is cranked or bent down at one end and provided with a journal for the wheel B, (see Fig. 3,) and at the other end is bent down and perforated with a hole, which forms 30 a bearing for a short rock-shaft, C, which carries the landside-wheel B'. To this axle is

35 attached the U-shaped metal frame D, Fig. 4, which is composed of flat iron bent over the axle and fastened to the same by clip a, the ends of which irons are bent down in rear of the axle and provided with bearings b for the plow-bail E, and which ends are also stiffened or braced by bracket-pieces c, Fig. 2, which extend from near the middle of the side bars of 40 the U-shaped frame down beneath the axle, and then to the lower bent end of said frame, where it is riveted or bolted, and terminates in an eye, d.

45 For simultaneously operating the bail and the landside-wheel, I locate upon the main frame D a hand-lever, F, having its fulcrum at e, and provided also with a locking device adapted to co-operate with a notched bar, G, to hold the lever in its several adjustments.

The lower end of this lever, below its fulcrum, 50 I connect, through two link-bars, f, with a cranked extension, g, from the bail, while above its fulcrum I attach a long link, h, passing over the top of the axle and jointed at its rear end to a crank, i, rigidly fixed to the short rock-shaft 55 C in rear of the axle. This rock-shaft is carried in the perforated bearing of the crank-axle at one end, and at the other end (next to crank i) is carried in a bearing in a pendent arm, j, bolted to the axle. Outside of the main axle 60 this rock-shaft is provided with a disk, k, to which is fixed a crank, l, carrying the journal for the landside-wheel.

Now, when the hand-lever F is drawn back it will be seen that a downward pull is exerted 65 upon the crank g of the bail and the plow is lifted out of the ground. At the same time, also, a downward push is exerted upon the crank i, which throws the landside-wheel down also to the level of the other wheel. When the 70 lever is, on the other hand, thrown forward a pull is exerted upon the crank i, raising the wheel B' the depth of the furrow, so as to run on the landside, and the bail is simultaneously let down to allow the plow to enter the ground. 75

By altering the relation of the crank l, or putting it in front of the axle, the device may be adapted to a right or left plow, as may be desired.

For connecting the plow-beam H with the 80 supporting-bail a clip-plate, m, is fastened to the beam and a swinging plate, n, is loosely supported at its middle upon the bail, and is connected to the clip-plate below by a bolt, so as to form a flexible joint. The plate n has 85 free lateral movement along the whole extent of the cranked portion of the bail, and its upper end is connected to the forward end of the clip-plate by a chain, o, Fig. 1, which prevents the plow from being pulled out of the ground 90 by being drawn forward under the bail by its draft-connection. These draft-connections consist of a ring at the forward end of the beam and two chains, also connected to the forward end of the beam, and extending back to and 95 hooking over the eyes d.

K is the tongue of the sulky-plow, which consists of a single straight wooden beam, which

is bolted to the cross-bar of the U-shaped frame, and also to the axle. L is the driver's seat, fixed upon the axle.

I am aware that it is not broadly new to connect the hand-lever of a sulky-plow with the bail and adjustable wheel, so as to raise the plow and lower the wheel by the same movement, and I do not claim this, but only my construction of parts for accomplishing such result.

Having thus described my invention, what I claim as new is—

1. The combination, with the bail having a crank-extension, g, and the wheel B', carried by a rock-shaft, C, having cranks i and l, of a lever, F, connected above its fulcrum with the crank i by a link, h, passing over the axle, and connected below its fulcrum and below the axle with the crank of the bail by link-bar f, substantially as shown and described.

2. The combination, with the bail and the plow-beam, of the clip-plate m, fastened to the beam, and the swinging plate n, connected at its middle to the bail and jointed to the clip-plate, and a chain, o, connecting the upper end of plate n with the forward end of the clip-plate, substantially as shown and described.

3. The combination, with the axle and the bail, of the U-shaped frame D, bent over and extended down below the axle in the rear thereof, and provided with bearings for the bail, and the braces e, passing beneath the axle and connecting the side bars of the frame D with its rear and pendent ends, as shown and described.

AXEL FERDINAND BERGQVIST.
